Attest

UNITED STATES PATENT OFFICE

HAROLD D. GRINNELL, OF PITTSFIELD, MASSACHUSETTS, ASSIGNOR TO THE G. C. A. MANUFACTURING COMPANY, OF PITTSFIELD, MASSACHUSETTS, A CORPORATION OF MASSACHUSETTS

LAMP-BASE REMOVER

Application filed December 29, 1928. Serial No. 329,287.

This invention aims to provide simple and efficient means for removing the bases of broken electric lamp bulbs and the like from their sockets.

In the accompanying drawings is shown, merely for illustrative purposes, one embodiment of the invention, wherein:

Figure 1 is a side elevation of the device, showing a detachable handle for use with the device when broken inverted lamp bases are to be removed, while dotted lines in said figure illustrate a type of operating device used in removing bases of broken lamps arranged in horizontal or inclined positions.

Fig. 2 is a longitudinal section through a lamp base and the gripper end of the base remover, the operative end of the base remover being shown in operative position against the rim of said lamp base; and

Fig. 3 is a transverse section taken approximately on the line 3—3 of Fig. 2, showing distortions of the lamp base due to pressure of the gripper thereagainst.

In the particular embodiment of my invention selected for illustrative purposes, I have shown in the drawings a lamp or other base 1 of the type used on electric lamps, which bases are generally composed of thin sheet metal forming threads on their outer surfaces by means of which said bases may be screwed into lamp sockets. Secured within these bases by means of sealing wax 2 or any suitable binder is a glass stem 3 for supporting the filament of the lamp, also a lamp bulb 4.

When glass bulbs are broken as they commonly are, it is sometimes difficult to remove the bases from their sockets, particularly when the sockets are attached to wall brackets or chandeliers placed in elevated positions at some distance from the floor.

To remove bases of broken lamps, I provide a device comprising grippers or gripping elements 5, herein desirably consisting of two plates 6 arranged approximately parallel but spaced sufficiently to receive between them the stem 3 of the lamp should the latter escape being broken when the bulb is broken.

Each plate 6 is provided with a series of serrations or saw-like teeth 9 in one of their

edges which, when pressed against the rim of the base, tend slightly to distort said rim, as shown at 7 in Fig. 3, for the purpose of effecting a grip upon the base so that upon the turning of said plates the base will be unscrewed from its socket.

The gripping plates are mounted in a suitable holder which desirably consists of a cylindrical hollow barrel 8 slotted at 10 and 12 to receive the plates 6, said slits extending longitudinally of the barrel for a portion only of its length to receive major portions of the plates 6, leaving the serrated ends thereof protruding from the slits as shown at 14.

The inner ends of the plates 6 are extended laterally on opposite sides at 16 beyond the periphery of the holder 8 to form shoulders 18 which seat against a collar 20 bored to fit snugly over the slotted end of said holder and maintain said plates seated firmly against the ends 22 of the slits 10 and 12, thus rigidly holding said grippers in said holder.

Screws 24 are herein provided for securing the collar 20 to said holder, although it is to be understood that the invention is not limited to such fastening means nor to the specific details of holder herein described.

The serrated edges of the plates 6 are desirably shown convexly curved, permitting the teeth thereof, within the rim of said base, to project into the sealing wax 2 and assist in providing a firmer grip upon the base.

A suitable handle is provided for the holder 8 for holding the grippers against the open end of a lamp base and for rotating said base to unscrew it from its socket. To this end a shaft 26 is secured to the holder 8, herein by means of a screw 28. The shaft 26 is desirably hollow, at least at the end secured to said holder to receive the stem 3 of the lamp. The opposite end of said shaft is provided with a spring pin or latch 30 for registering a hole 32 shown dotted in the side of the socket 34 of an operating pole 36 shown in part at the right of Fig. 1 and detached therefrom.

The type of handle shown in Fig. 1 is for use in unscrewing bases from sockets arranged perpendicularly or nearly so or such

as are reachable in an axial direction, but there are many bases so arranged that an axial approach is impossible and must be operated from a point substantially at right angles to the axis, in which case I provide an enlargement 38 secured upon the shaft 26. This enlargement is desirably made cylindrical and about the size of an electric light bulb so that it may be grasped by any suitable lamp remover adapted for such purposes, such for example as disclosed in United States Patent No. 1,752,737, issued to this applicant April 1, 1930. The operative end of such a device is shown in dotted lines at 15 40 (see Fig. 1 of the drawings).

The teeth 9 of the gripping plates are V-shaped and when pressed against the rim of the lamp base the inclined sides of said teeth force the portions of the rim engaged by said teeth either outwardly or inwardly according to which side of the tooth engages said rim thereby indenting said rim as indicated at 7, Fig. 3, which indentations prevent the teeth from slipping around said rim when the plates are rotated.

From the foregoing description it will be apparent that the device described herein is capable of easily removing bases of broken lamps from practically any position and even though the lamp bulbs are entirely or only partially destroyed. If only partially destroyed, the plates 6 upon being rotated will ream out the remaining glass protruding from the end of the base if said glass is incapable of providing sufficient purchase for unscrewing said base.

The invention is not limited to the specific form shown.

Claims:

40. 1. In a lamp base remover, in combination, a holder and a blade-like member carried by the holder and having indented edge portions for engaging the lamp base at opposed points in a line tangent to a circle about the axis of which the holder is adapted to be rotated.
2. In a lamp base remover, in combination, a holder and base gripping means, including a transversely arranged blade-like portion carried by the holder and having indented portions for engaging the rim of the base at opposed points within a segment of the circle formed by said rim.
3. In a lamp base remover, in combination, a holder and a pair of blades carried by the holder and arranged on opposite sides of the axis of the holder, each of said blades having indented portions adapted to engage the rim of the lamp base at opposed points.
4. A lamp base remover for application to lamp bulbs having a base portion rotated with the lamp bulb during removal, and including a handle, a tubular member carried by the handle, and a pair of blades carried by the tubular member, each having serrated 65 edge portions arranged transversely of the

lamp base, said blades being arranged on opposite sides of the longitudinal axis of the lamp bulb.

5. In a lamp base remover, base gripping means including spaced transversely arranged members each having a base engaging edge provided with a series of oppositely inclined surfaces to respectively engage the rim of the lamp base at opposed points.

6. A base remover comprising, in combination, base gripping elements including spaced plates having convexly curved edges provided with saw-like teeth, a holder for said plates, a shaft secured to said holder and means to engage said shaft to move the teeth of said spaced plates into engagement with the rim of the base and for turning said base.

7. In a device of the character described, in combination, gripper plates, a holder for said plates including a hollow barrel having slits to receive said plates extending longitudinally from one end of said barrel for a portion of the length thereof and a collar surrounding the slotted end of said barrel for maintaining said plates in said slits.

8. In a device of the character described, in combination, gripper plates provided with shoulders near their inner ends, a holder for said plates including a hollow barrel having slits to receive said plates extending longitudinally from one end of said barrel for a portion of the length thereof and a collar surrounding the slotted end of said barrel against the shoulders of said gripper plates for maintaining said plates in said slits.

9. In a device of the character described, in combination, gripper plates, a holder for said plates including a hollow cylindrical barrel having slits extending longitudinally from one end of said barrel for a portion of the length thereof and a collar surrounding the slotted end of said barrel for maintaining said plates in said slits.

10. A base remover comprising, in combination, a base removing device including a pair of spaced approximately parallel plates each having V-shaped notches in one edge to engage the rim of the base for the purpose of crimping said rim and for providing gripping surfaces to effect unscrewing of said base.

11. A lamp base remover comprising, in combination, lamp base gripping means, a holder for said gripping means, a shaft upon which said holder is secured and an enlargement attached to said shaft capable of being gripped by a bulb removing device to effect the turning of the lamp holder against the lamp base whereby said base may be unscrewed from its socket from a position at an angle to the axis of the base.

In testimony whereof, I have signed my name to this specification.

HAROLD D. GRINNELL.
